CHILD'S EDUCATIONAL APRON

Anne E. Goldstein, 117 Juniper St., Burlington, N.J.

Filed Apr. 8, 1960, Ser. No. 60,096

Term of patent 14 years

(Cl. D3—26)

The figure is a front elevational view of a child's educational apron showing my new design.

The rear of the apron is substantially plain and the belt continues around the back, tapering in width from the large end at the left to the narrow end shown at the right of the apron.

I claim:

The ornamental design for a child's educational apron, substantially as shown and described.
